FAUCET

Harold O. Seltsam, Cleveland, Ohio, assignor to Tomlinson Industries, Inc., Cleveland, Ohio, a corporation of Ohio

Filed Aug. 5, 1963, Ser. No. 76,096

Term of patent 14 years

(Cl. D2—3)

FIG. 1

FIG. 2

FIG. 4

FIG. 3

FIG. 5

FIG. 7

FIG. 6

FIG. 1 is a perspective view of a faucet, showing my new design;

FIG. 2 is a side elevation view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is an enlarged fragmentary side elevational view partly in section thereof; and

FIG. 8 is a section view taken along line 8—8 of FIG. 3.

The dominant features of my design reside in the portions shown in full lines.

I claim:

The ornamental design for a faucet, as shown and described.
